Atty's

UNITED STATES PATENT OFFICE.

FREDERICK HUNTER, OF BOSTON, MASSACHUSETTS.

SHOE.

Application filed December 28, 1922. Serial No. 683,250.

To all whom it may concern:

Be it known that I, FREDERICK HUNTER, a citizen of the United States, and a resident of Boston, county of Suffolk, State of Massachusetts, have invented an Improvement in Shoes, of which the following description, in connection with the accompanying drawing, is a specification, like characters on the drawing representing like parts.

This invention relates to improvements in shoes and particularly of the type in which the sole has an exaggerated inflared toe portion, that is to say a toe portion the inside of which projects or swings inwardly a considerably greater distance from the longitudinal axis of the shank and sole than the outward projection or flare of the sole; shoes of this type being generally known in the trade as "Natural" shoes, and otherwise known to the trade as "Ground Gripper", "Educator", etc. The sole of shoes of this type have heel portions which follow in conformation of the heel of the foot and present a curved rear portion and side portions which converge inwardly toward the shank of the shoe to a distance beyond the usual breast edge of the heel of the shoe.

In the manufacture of shoes the counters have heretofore been constructed to conform to the shape of the heel and consequently to follow the converging lines of the forward side portions of the heel. This form of counter is correct as to the housing of the outside line of the foot as the convergence toward the axis of the shank is but slight, but upon the inside of the heel of the shoe the convergence is much greater and causes the counter to produce a resistance to the inside of the heel of the foot of the wearer so that when the weight of the body is imposed upon the heel of the foot it causes a soft facia at the inner portion of the heel to be condensed and consequently forced outwardly by the portion of the counter which is engaged by it. This tends to throw the foot outwardly with respect to the line of the upper which lies in a plane substantially tangential to the inner curved

face of the heel and the inflare of the toe portion of the shoe. Consequently the foot is forced outwardly from its normal position with respect to the sole and the outer side of the foot particularly along the outer ball portion thereby distorting the outer portion of the upper and eventually causing it to project beyond the outside of the sole. This is a defect which is commonly found in shoes particularly of the so-called "Natural" type above described.

The object of the present invention is to prevent the displacement of the foot in the shoe and to permit the foot to assume and maintain its upper relation upon the sole. This is accomplished by providing a counter of stiff material which conforms to the shape of the heel, but which terminates on the inside of the heel portion substantially in a plane tangential to the inside of the heel and the inflare of the toe portion.

Other objects and features of the invention will more fully appear from the following description and the accompanying drawing and will be pointed out in the claims.

In the drawing:

Fig. 1 is an elevation of a shoe, viewed from the inside, a portion of the upper being broken away to illustrate the counter embodying the present invention;

Fig. 2 is a plan view of a sole showing a preferred form of counter, embodying the invention, in section and illustrating in dotted lines the usual form of counter and the position of the foot upon the sole caused by such counter, and also illustrating in dot and dash lines the normal position of the foot upon the sole which is procured by the use of the present invention.

The shoe illustrated in the accompanying drawing comprises the usual sole 1 having a heel 2 and an upper 3 of flexible material in which the shoe is housed and in which the line 4 of the inside of the upper, when viewed from above, lies in a vertical plane substantially tangential to the heel and the inside flared portion of the toe.

The sole of the shoe illustrated in the accompanying drawing is of the so-called "Natural" type and comprises a heel por-

tion 5 having a curved rear end 6 and side portions 7 and 8 of a curvature which converges more or less toward the longitudinal axis 9 of the shank and sole. From the heel 5 portion 7 the outer edge of the sole curves outwardly with respect to the axis of the sole, presenting an outwardly flared portion 10. The edge 11 of the sole then curves inwardly to the toe 12. The inner edge of 10 the sole converges from the inner side portion 8 of the heel along a curve 13 which approaches much closer to the longitudinal axis of the shank and sole than the corresponding outer edge portion. The inner edge 15 then curves more abruptly outwardly along the line 14 to present the inflared toe portion and thence presents an inward curve 15 to the toe portion 12 of the sole. The usual counter conforms to the curvature of the 20 rear and side portion of the heel and extends along in parallelism with the edges of the sole to the breast 16 of the heel, or more usually from one-fourth to one-half inches beyond the breast of the heel.

25 By reason of the fact that the convergence of the outer edge of the sole toward the axis of the shank is relatively slight the outer portion of the counter permits the foot, when placed in the shoe, to assume its proper 30 position. The curvature of the inner front portion 13 of the heel, however, is such that the counter in following this line of curvature extends well beyond the line 4 of the inside of the upper, such position of the 35 counter being illustrated by the dotted line construction 17 in Fig. 2. As a consequence of this excessive inward curvature of the stiff forward inside portion of the counter the inner forward portion of the heel of the 40 wearer engages the forward inner end portion of the counter 17 and forces the forward portion of the heel outwardly thus displacing the toe portion of the foot from its normal position, as indicated in dot and dash 45 lines, to the position indicated in dotted lines in Fig. 2.

It will be noted that although the forward inner end portion 17 of the usual counter engages the soft fascia of the front portion 50 of the heel of the foot the portion of the heel thus engaged is opposite the rigid os calcis bone and inasmuch as the skeleton structure of the foot is rigid against lateral movement, while flexible with respect to vertical 55 movement which is used in the act of walking, the pressure of the counter upon this forward portion of the heel necessarily swings the toe portion of the foot outwardly in the manner above described.

60 As the flexible upper will yield to such displacement it soon becomes permanently distorted and overhangs the outer edge of the sole as will be observed to be a condition in the majority of partially worn and old 65 shoes. Furthermore, when the foot is thus

displaced it loses a considerable portion of the bearing surface of the sole which should be used as the weight-bearing surface for the foot.

The present invention contemplates the provision of a counter which will not press against the inner forward portion of the heel. This is accomplished by providing a counter having a curved rear portion 18 conforming to the contour of the rear edge 70 of the heel and an outer side portion 19 which may extend along the outer side of the heel portion to or beyond the breast portion 16 of the heel and an inner side portion 20 which is a continuation of the curved 75 rear edge portion of the counter, but terminates well back of the breast of the heel preferably in a plane tangential to the inside edge of the heel and the inflared toe portion 80 of the sole. The line 4 of the upper lies substantially in this plane so that the forward inner portion of the heel of the wearer will engage the flexible upper which will yield sufficiently to enable the foot to assume its normal position as illustrated in dot and dash lines in Fig. 2. As illustrated in Figs. 1 and 2 the front inner edge 21 of the counter intersects the sole about midway between the position of the breast of the heel and the rear edge of the heel and extends upwardly 95 and rearwardly along such curves as may be most desirable to accomplish the purposes set forth and to present a neat appearing shoe.

100 It will be understood that while the invention is described more particularly with reference to shoes having soles provided with exaggerated inflared toe portions, it is equally applicable to shoes of any other type in which the convergence of the forward inner side of the heel portion toward the axis of the shank is such as to cause a counter conforming thereto to press upon the forward inner portion of the heel.

Having thus described the invention, what 110 is claimed as new, and desired to be secured by Letters Patent, is:

1. A shoe comprising a sole having an inflared toe portion and a heel portion the side edges of which converge toward the longitudinal axis of the shank of the sole and an upper of flexible material, a counter of stiff material conforming to the shape of said heel and terminating on the inside of the heel portion substantially in a plane tangential to the inside of the heel and inflare of the toe portion of the sole, whereby pressure upon the forward inner portion of the heel of the wearer will be prevented and by reason of the flexibility of the upper the foot 115 will assume and maintain its proper position on the sole and thereby avoid outward distortion of the upper relatively to the sole.
2. A shoe comprising a sole having an inflared toe portion and a heel portion the side 120

edges of which converge toward the longitudinal axis of the shank of the sole and an upper of flexible material, a counter of stiff material conforming to the shape of the heel 5 extending along the outer side of the heel, around the rear portion of the heel, and terminating substantially midway of the inside of the heel whereby pressure upon the for-

ward inner portion of the heel of the wearer will be prevented and by reason of the flexibility of the upper the foot will assume and maintain its proper position on the sole and distortion of the shoe avoided. 10

In testimony whereof, I have signed my name to this specification.

FREDERICK HUNTER.
